WASHING MACHINE

Harry G. Sutton, Syracuse, N. Y., assignor to
 United States Hoffman Machinery Corporation,
 New York, N. Y., a corporation of Delaware

Application April 3, 1940, Serial No. 327,715

3 Claims. (Cl. 68—139)

This invention relates to washing machines for dry cleaning by the use of evaporative cleaning fluids.

Machines of the prior art are often subject to unsightly leakage of fluid over the machine front. The present invention aims to avoid such leakage by providing a liquid return to the tub of the machine, and by providing a receptacle into which liquid flowing along an open door or from clothes removed from the washing cylinder may drain and be returned to the liquid supply. It is also proposed to combine with the liquid control system semi-automatic means for filling or refilling the tub and to provide for safety and convenience of operation.

Numerous advantages will appear from the following specification. In the drawings:

Figure 1 is a front elevation of one form of washing machine embodying the present invention, the view indicating in dotted lines the location of the washing cylinder and tub in the machine casing;

Fig. 2 is a vertical sectional view taken substantially on the line 2—2 of Fig. 1;

Fig. 3 is a detailed sectional view, on an enlarged scale, of the washer door and the liquid overflow return structure which is an important feature of the invention;

Fig. 4 is a face view of the double door assembly of the washer;

Fig. 5 is a diagrammatic view of the complete washer, together with the tanks and piping which provide for draining of the washer and refilling of the same;

Fig. 6 is a detail view, partly in section, of a combined manually and float operated system for controlling the flow of liquid into the washer;

Fig. 7 is a side elevation of a portion of the mechanism of Fig. 6, looking from left to right in Fig. 6;

Fig. 8 is a detail view of the automatic safety lock provided between the washer door and the controlling switch of the driving motor; and

Fig. 9 is a fragmentary view showing the switch controlling mechanism in both the "on" and "off" positions of the switch.

In Fig. 1 the washing machine casing shown is of panel construction embodying side panels 12 and 13, a front panel 15 and a rear panel 14. An arcuate member 16 enclosed by these panels and sealed thereto forms the usual washing machine tub, in which the washing cylinder rotates. This cylinder, of the overhung type, includes a perforated cylindrical wall 17 having a closed rear wall or head 18 attached to a

spider 19 carried by a shaft 21 rotatable in a bearing 22. The rear panel 14 carries stiffening members 23 which support the bearing 22 and a driving motor 28 which actuates the shaft 21 through a belt 27 and worm gearing 26. The shaft 21 is sealed with respect to the rear panel by a packing 24 carried in a removable panel section 25. The cylinder is closed at the front by a head or wall 29 having a central access opening 31 bounded by an outstanding marginal flange 32, and contains radial flights or ribs 20 which give the clothes to be washed a cascading movement during rotation of the cylinder.

The forward wall 15 of the machine casing 13 contains an opening in alignment with the cylinder opening 31 and this opening contains a door frame 34 in the form of a casting having a front stiffening flange 35 which overlies the margin of the opening in the casing and is attached to the casing by bolts or rivets 36. Flange 32 on the cylinder projects into the door frame 34 to prevent pinching of goods between the cylinder and the door frame.

The door frame 34 is adapted to support two doors, the inner door 52 being mounted on a web 49 formed integrally with the casting 34. The door seals against a flange 33 extending entirely around the opening and eccentric with respect to the outer door opening and the cylinder opening 31. Hence it is wider at the bottom of the door opening than at other points and provides a web 51. The web 51 is in spaced relation to web 49 which supports the door 52. The space between these webs 49 and 51 is in communication with the interior of the washing machine tub through a drainage opening 58, so that any liquid overflowing the web 51 or escaping from door 52 into this space may flow back into the tub without running over the outside of the casing.

The frame 34 also supports the outer door 37 through hinges 38, pintle 41 and a Y-shaped bar 39. The door is attached to the bar 39 by bolt 42, the bar being recessed at 44 to receive a spring 45 which affords a resilient connection between the bar and the door. Latch bar 46 carrying handle 48 cooperates with keeper 47 to lock the door.

The inner door prevents liquid from being splashed against the outer door and is preferably of elliptical form to minimize such splashing. The elliptical opening has its top margin conforming to the circular portion of the top of the outer door so that liquid splashed by the flights as they strike the liquid surface is pre-

vented from escaping. The door 52 is held in latched position by a latch 54 pivoted at 55 and cooperating with a dependent stop 56 on frame 34. The outer door is provided with interference lugs 57 which may straddle the latch handle 54 in its locked position only, to insure that the outer door cannot be latched until the inner door is in closed position, and latched.

Inasmuch as the machine during its operation splashes liquid against the inner door as each rib in the cylinder strikes the surface of the liquid in the cylinder, it is desirable to provide for the drainage of the liquid back into the system. The door is arranged for this purpose to swing about horizontal hinge 53 and into a sump 59, as indicated in Fig. 4. The sump is carried at the front of the casing by supporting member 60 and flange 35 on casting 34. Liquid draining from this sump passes through openings 64 in false bottom 62 and then through connection 61 to a drain tank 63 vented at 81, see Fig. 5. The sump 59 is of sufficient capacity to hold a full charge of articles removed from the washing cylinder, and permits drainage of the same while a new charge is being placed in the washing cylinder, or during a subsequent washing operation.

In practice it is advisable to provide the washing machine with emptying and refilling means, as well as means for taking care of the overflow of liquid from the machine tub. Such a system is disclosed in Fig. 5 of the drawings, wherein there is included a storage tank 66 for cleaning fluid, this tank having the usual vent 67. Pipe 65 is an overflow connection from the washer tub, whereas line 73 is a drain connection for the tub leading to the drain tank 63. Interposed in the line 73 is a trap 74 for buttons or the like, this trap discharging into line 76, 78 which includes control valves 75 and 79. A pump 77 connected to line 76 may be actuated to return liquid either from the drainage tank 63 or from the line 73 to the storage tank 66 through line 69.

When the washer is operating, valve 75 will be closed, and valve 79 may be opened when liquid is to be pumped to the storage tank. Both valves may be opened to drain the washer tub or valve 79 may be closed and valve 75 opened to drain the tub to the pump and thence return the liquid to the storage tank. A line 68 connected to the bottom of tank 66 forms a filling connection for the washer tub and contains a valve 83 for controlling the flow of liquid from the storage tank to the tub, and this valve is biased toward closed position. Manual means are provided for opening the valve 83, and automatic float controlled means for latching that valve open, if opened when the liquid level in the tub is low but not latching it if the liquid level is substantially up to overflow connection 65. This controlling mechanism, shown in detail in Figs. 6 and 7, includes a float chamber 71 connected with the bottom of the tub through a liquid level equalizing connection 82. The valve 83 is biased to closed position by a pair of springs 95 reacting between a stirrup 96 attached to the float chamber, and forks 97 of a lever 98 pivoted at 99 and connected to a valve actuating lever 94 through a link 101. The lever 94 has at one end a cam surface 72, which serves as a latch for the valve 83 to hold the valve open when the liquid level is low, and which is responsive to a float 84 in chamber 71.

The lever 98 includes an arm 102 which may be actuated by hand lever 93. This hand lever

93 is pivoted at 108 and biased to the position shown by a spring 109 acting on a lever 111. A rod 105 pivoted to lever 93 is in sliding engagement with a guide 103 containing a slot 107 for cooperation with a block 106 pinned to the rod 105. The guide 103 is attached to the arm 102 at 104. When the valve 83 is closed by spring 95, and the hand lever is released, the block 106 occupies the end of the slot 107 as indicated. 10 Movement of the handle 93 to the left opens the valve 83 against the bias of springs 95.

It is desirable to provide for automatic filling of the tub to a proper level in response to movements of the float 84 in the chamber 71. With 15 the arrangement shown, the valve 83 may be opened by valve lever 93 at any time regardless of the position of the float 84. If the level is too low when the valve 83 is opened, roller 89 carried on the lower arm 88, of lever 91 engages the cam 20 72 to hold the valve open. When the float rises to actuate the arm 85 and move it against stop 92 on the arm 91, the roller is caused to swing to the right and release the cam 72 permitting springs 95 to close the valve. In its lowermost 25 position the float lever 85 engages a stop 86 on the top of the float chamber and permits engagement of roller 89 and the cam 72. Stop 90 on the lever 85 limits the movement of lever arm 91 toward the left. Consequently, when the valve 30 83 is opened manually by manipulation of lever 93, it will be closed at once by springs 85 upon release of handle 93, if the roller 89 occupies the position shown, that is if the liquid in the tub is at proper level as determined by the float 84 in its extreme upward position. If the liquid level is down, the float is below its extreme upward position, and the roller 89 will engage cam 72 to hold the valve open until the liquid reaches a proper level and float 84 releases the valve. Consequently, the operator can never, through inattention, cause the washer to be filled to overflowing because the float 84 automatically closes the valve when a proper level is reached.

In addition to the safety feature of liquid level 45 control, the washer is preferably provided with means for preventing the motor from being started and left running while the outer door is unlatched. For this purpose there is associated with the switch 128 which controls the driving 50 motor 28, a safety device which permits operation of the motor only so long as the switch handle is held against biasing means when the outer door is unlatched.

The switch 128 has a lever 129 which may be 55 actuated by switch handle 132 through member 121 and fork 131, the "on" position being indicated in full lines in Fig. 9. Attached to the member 127 and movable with the switch handle is a lever 125 having an adjustable stop 126. 60 Attached to this lever 125 is a rod 122, the weight of which tends to bias the switch to the dotted line position of Fig. 9 but is insufficient to move it. The rod 122 carries a block 121 which is 65 slidable in a slot 123 in guide 119, carried by rod 118. Rod 118 is connected to one end of lever 116 pivoted at the back of the casing at 117. The connection is completed by rod 115, shaft 114 and lever 113 at the front of the casing. The lever 113 carries a pin 112. When the door is 70 latched, the latch 46 engages the pin 112 to move the parts to the position shown in Fig. 1, in which the stop 120 in guide 119 is lifted free of the block 121, and to permit free movement of the switch handle from one position to another. The switch will remain where placed until the latch 75

46 is released by handle 48. When the latch 46 is released, the weight of the parts is sufficient to move the stop 120 against block 121 and to move the arm 125 to the dotted line position of Fig. 9. In this latter position, the switch may be closed only so long as it is held against the bias affecting the arm 125 and imposed by the weight of the parts above it. Whenever the switch handle is released, under these conditions, the switch is moved to "off" position as shown in dotted lines in Fig. 9.

In consequence of the features described above, complete freedom of leakage of cleaning fluid over the machine casing is avoided, semi-automatic refilling of the washer tub with cleaning fluid is provided for, and continuing operation of the driving motor with the machine door open or otherwise in improper condition is avoided. The motor may, however, be started with the outer door unlatched, by holding the switch 20 closed. This makes it possible to bring the washing cylinder to any desired position for an unloading operation.

The details described are for purposes of illustration only and are capable of variation within the scope of the claims without departing from the spirit and scope of the invention.

What is claimed is:

1. A washing machine comprising a casing having a liquid containing tub; an overhung perforate cylinder rotatably mounted in said tub, said cylinder having an access opening in its end remote from its mounting; a door frame member mounted in said casing in front of the opening in the end of the cylinder, said frame member having an inwardly spaced web which is close to the end of the cylinder and defines at least the lower portion of an elliptical opening whose major axis is horizontal and whose lower margin is

above the level of liquid in the tub; and two doors, an inner door for closing said elliptical opening and an outer and larger door sealing against said door frame, there being a drain passage to the tub between said web and the remainder of the door frame.

2. A washing machine comprising a casing having a liquid containing tub; a perforate cylinder rotatably mounted in said tub, said cylinder having an access opening in one end; a door frame member carried in said casing in front of the opening in said cylinder, said member having an elliptical opening adjacent said cylinder with its longer axis horizontally disposed and its bottom above the liquid level in said tub, and a second opening at the front and spaced from the first; a door for each of the openings in the door frame member; a liquid sump disposed forwardly of and below the level of said doors and into which the door for the elliptical opening swings and into which all liquid from said door drains when the door is in open position; a liquid drain tank; and means for delivering liquid from said sump to said tank.

3. In a washing machine of the horizontal cylinder type, a casing having a door opening therein; a liquid containing tub in said casing; a drum mounted in said casing and arranged to rotate in the liquid in said tub, said drum having an opening in one end and in substantial alignment with the opening in the casing; and means including two independent spaced non-rotatable doors hinged to the casing, one inwardly of the other and each independently of the other sealing the opening in the casing, said means including a drain passage for returning to the tub any liquid which may escape from the inner door opening.

HARRY G. SUTTON.
